(57) **CLAIM**

What is claimed is the ornamental design for a switching device with front cover, as shown and described.

DESCRIPTION

FIG. 1 is a front perspective view of a switching device with front cover according to the invention.

FIG. 2 is a rear perspective view of a switching device with front cover according to the invention.

FIG. 3 is a bottom perspective view of a switching device with front cover according to the invention.

FIG. 4 is a front view of a switching device with front cover according to the invention.

FIG. 5 is a left side view of a switching device with front cover according to the invention.

FIG. 6 is a right side view of a switching device with front cover according to the invention.

FIG. 7 is a rear view of a switching device with front cover according to the invention.

FIG. 8 is a top view of a switching device with front cover according to the invention; and,

FIG. 9 is a bottom view of a switching device with front cover according to the invention.

The broken line portions of the figure drawings are included to show portions of the article that form no part of the claimed design.

1 Claim, 9 Drawing Sheets
